COMBINED HEADER AND TRACK SUPPORT MEMBER FOR A SLIDING PANEL

Robert A. Miller, Plainville, Conn., assignor to The
Stanley Works, New Britain, Conn., a corporation of
Connecticut

Filed Apr. 22, 1968, Ser. No. 11,551

Term of patent 14 years

Int. Cl. D25—03

U.S. Cl. D13—6

FIG. 1

FIG. 2

FIG. 1 is an end view of a combined header and track support member for a sliding panel showing my new design, the broken line showing of a track and screw being for illustrative purposes; and

FIG. 2 is a perspective view of the combined header and track support member of FIG. 1.

I claim.

The ornamental design for a combined header and track support member for a sliding panel, as shown and described.
